John Jacob Lubberts and Lambert James Mulder,
Grand Rapids, Mich., assignors to Tomlinson of High Point, High Point, N. C., a corporation of North Carolina

Application November 12, 1946, Serial No. 134,686

Term of patent 14 years

(Cl. D5—4)

To all whom it may concern:

Be it known that we, John Jacob Lubberts and Lambert James Mulder, citizens of the United States, residing respectively at 47 Packard Ave. S.E., Grand Rapids, in the county of Kent and State of Michigan, and 1416 Sherman Street S.E., Grand Rapids, in the county of Kent and State of Michigan, have invented a new, original, and ornamental Design for a Bed, of which the following is a specification, reference being had to the accompanying drawing, forming a part thereof, wherein—

We claim:

The ornamental design for a bed, substantially as shown and described.

JOHN JACOB LUBBERTS.

LAMBERT JAMES MULDER.
